UNITED STATES PATENT OFFICE.

FREDERICK G. FOLBERTH AND WILLIAM M. FOLBERTH, OF CLEVELAND, OHIO, AS
SIGNORS TO TRICO PRODUCTS CORPORATION, OF BUFFALO, NEW YORK, A COR-
PORATION OF NEW YORK.

WINDSHIELD CLEANER.

Application filed October 29, 1923. Serial No. 671,493.

This invention relates to windshield cleaners, and more particularly to motor operated windshield cleaners.

An object of the invention is the provision 5 of a windshield cleaner motor of the general type disclosed in a prior patent to William M. Folberth, No. 1,424,890, granted August 8, 1922, (Reissue No. 15,502), having a closure plate of the motor arranged on the side 10 of the cylinder substantially equidistant from the ends of the cylinder and having passages arranged in said closure plate adapted to align with conduits formed in the wall of the cylinder and connected to the 15 opposite ends of the cylinder.

A further object of the invention is the provision of valve shifting mechanism of the general type disclosed in said patent in which the stem of the hand operated control 20 valve serves as a stop to limit the movement of the pivoted arms forming a part of the automatic valve mechanism which alternately connects the opposite ends of the cylinder to a source of suction or pressure.

25 A further object of the invention is the provision of a connecting member for the pistons formed of sheet metal having openings stamped therein for the reception of gear teeth and having curved ends to engage 30 one of the pivoted arms of the valve shifting mechanism to operate the valve.

In the accompanying drawings, we have shown one embodiment of the invention. In this showing:

35 Figure 1 is a perspective view of the motor cylinder with the closure plate removed,

Figure 2 is a central vertical transverse sectional view,

40 Figure 3 is a perspective view of the closure plate and valve mechanism,

Figure 4 is a central vertical longitudinal sectional view,

45 Figure 5 is a plan view, parts being shown in section,

Figure 6 is a front elevation of the segmental gear,

Figure 7 is a perspective view of one of the pivoted arms of the valve shifting mechanism,

50 Figure 8 is a similar view of the other arm, and,

Figure 9 is a front elevation of the closure plate.

Referring to the drawings, the reference 55 numeral 1 designates a casing having heads 2 arranged on opposite ends, the heads being preferably secured to the cylinder by means of bolts 3, which are received in openings formed in enlargements 4 at the opposite 60 ends of the cylinder. A pair of spaced pistons 5 are arranged within the cylinder. The pistons may be formed of a pair of disks having a sheet 6 of rubber or other suitable packing arranged between them. The packing 65 is preferably of larger diameter than the interior of the cylinder, forming a flange 7. The parts of the piston are secured to each other by suitable fastening element 8. The pistons are adapted to be retained in spaced 70 relation by a connecting member 9, which is formed of sheet metal and is provided with inclined portions 10 adjacent each edge. Beyond the inclined portions, the member is provided with transverse portions 11, hav- 75 ing openings for the reception of the screw 8 and the ends of the member are curled, as at 12. Intermediate the ends, the connecting member is provided with a plurality of spaced openings 13, adapted to serve as teeth 80 to mesh with suitable gearing and transmit the movement of the pistons to a shaft.

The cylinder is provided with a relatively large opening intermediate its ends, having a flat face 14. A closure member 15 is 85 adapted to be arranged over this opening, the closure member being provided with openings 16, for the reception of suitable fastening elements which are received in openings 17 in the flat faces 14 to retain the 90 closure member in position. The closure member is provided with an enlargement 18, on its inner face, substantially in the form of a vertical rib and a second enlargement 19 in the form of a horizontal rib. A pas- 95 sage 20 extends into the bottom of the closure member and this passage is adapted to be connected to a source of differential pressure, such as the intake manifold of the engine of a motor vehicle (not shown), by 100 means of a conduit 21. A sleeve 22 extends from the bottom of the rib 18 and this sleeve is provided with a threaded bore for the re- ception of a valve stem 23. Beyond the bore, and in alignment therewith, there is 105 provided a passage 24, communicating with the inlet passage 20. The valve stem is pro- vided with a conical face 25, forming a valve

and engaging a valve seat formed at the point where the bore and passage meet. The passage 24 communicates with a vertical passage 26 which extends upwardly from the bottom of the closure member and the lower end of this passage is closed by a suitable plug 27. The upper end of the passage 26 communicates with an inwardly extending passage 28, extending through the rib 18 to the inner face of the closure plate. As shown in Figure 5 of the drawings, the rib is provided with passages 29 and 30, arranged on opposite sides of the main passage 28 and these passages in turn communicate with passages 31, formed in the closure plate and extending longitudinally of the cylinder when the closure plate is in position. The ends of the passages 31 communicate with the interior of tubes or conduits 32 formed on the interior of the cylinder and communicating with the ends of the cylinder through ports 33. As shown in Figures 1 and 5 of the drawings, the ends of the conduits 32 are provided with beveled faces 34. The side edges of the closure plate are similarly provided with beveled portions 35, adapted to fit over the beveled faces 34 and bring the passages 31 in alignment with the interior of the conduits 32. By means of this beveled arrangement, the necessity of cross drilling is eliminated and the longitudinal passages in the closure plate may be aligned with the longitudinally extending tubes or conduits.

Suitable valve mechanism controlled by the operation of the piston is arranged in the cylinder to alternately connect the passages 29 and 30 to the passage 28. As shown, the closure plate is provided with an enlargement 36, arranged above the rib 18 and the sleeve 22. A pin 37 is mounted in this enlargement and this pin serves as a pivot for the valve shifting mechanism. The valve shifting mechanism consists of a pair of arms shown in detail in Figures 7 and 8 of the drawings. A substantially L-shaped arm 38 is arranged on the pin, the upper end of the arm being provided with an up-struck portion which is bent over, as at 39. The body portion of the arm is provided with an opening 40 and the portion 39 is provided with an opening 41 arranged in alignment therewith. These openings are adapted to receive the pivot pin to form a substantial support. The lower portion 42 of the arm is arranged over the sleeve 22, as shown in Figure 2 of the drawings, and is provided with a pair of depending arms or fingers 43, adapted to engage the sides of the sleeve to limit the movement of the arm. The outer end of the arm is extended, as at 44, and is provided with an opening 45, for the reception of a pin 46. This pin forms the valve stem and carries a substantially cup-shaped valve 47, which is adapted to

cover the end of the passage 28 at all times and to cover the end of one of the passages 29 and 30 depending upon the position of the arm 38, to connect one of the latter passages to the passage 28. A suitable spring 48 is arranged on the valve stem to retain it on its seat. The upper portion of the arm 38 is extended forwardly at a slight angle and is provided with a notch 49. Beneath the notched portion, there is provided an opening 50, formed by the cut-out portion 39.

The other pivoted arm shown in detail in Figure 8 of the drawings, consists of a relatively wide body portion 51, having a central opening or cut-out portion 52. This arm is provided with an angularly extended portion 53, at the top, and the end of the angularly extending portion extends downwardly parallel to the body portion, as at 54. The downwardly extending portion 54 and the body portion are provided with openings 55 and 56 for the reception of the pivot pin 37. As shown in Figure 2 of the drawings, when the arms are in assembled position, the angular portion 53 of the second arm extends through the opening 50 in the first arm and the depending portion 54 is arranged on the opposite side of the first arm so that the first arm is substantially embraced by the upper end of the second arm. The second arm is provided with depending fingers 56' at its lower end and is further provided with a notch 57. A coil spring 58 is arranged between the arms, the coil spring being provided with hooks 59 on its ends adapted to be received in the notches 49 and 57. As shown, in Figure 2 of the drawings, the body portion of the spring fits within the cut out portion 52 of the second arm. The fingers 56' are arranged on opposite sides of the valve stem 23 and are adapted to engage it to limit the movement of the arm, said valve stem 23 and said sleeve 22 combining to form a stop common to both limit fingers 43 of the valve carrier 128 and both limit fingers 56' of the spring positioning member 51.

The enlargement 36 is provided with a bore for the reception of a shaft 60. The inner end of this shaft is squared, as at 61, and is adapted to receive a plate 62, which is arcuate shaped and provided with teeth 63, forming a segmental gear. The teeth 63 mesh with the teeth formed by the openings 13 in the connecting member 9. As shown, the segmental gear is provided with an arcuate slot 64 for the passage of the pivot pin 37 of the valve shifting arms. The shaft 60 is adapted to be passed through an opening in the windshield frame, as shown in Figure 2 of the drawings. As shown, the device is adapted to be applied to a windshield of the usual construction, consisting of a pane 65 of glass or other transparent material, mounted in a metal

- frame 66. The outer end of the shaft is adapted to receive a resilient cleaner arm 67, having a retaining member 68 on its lower end. This retaining member is adapted to receive the cleaner element consisting of a backing strip 69 of metal or other rigid material and a flexible strip 70 of rubber or similar material, which passes over the surface of the windshield to clean it. The closure plate is further provided with openings 71, adapted to receive bolts 72, shown in dotted lines in Figure 5 of the drawings, which pass through the frame of the windshield to retain the motor casing in position.
- In operation, with the parts in the position shown in Figures 4 and 5 of the drawings, the left end of the cylinder is connected to the source of suction or pressure due to the position of the valve connecting the ends of the passages 28 and 30. The pistons are then moving toward the left. In the position shown in Figure 4 of the drawings, the curled right end 12 of the connecting member is in engagement with one of the fingers 56' formed on the valve shifting arm 51. The movement of the piston swings this arm on its pivot and when the arm reaches a position where the lower end of the spring 59 passes the center line of the pivot pin 37, the tension of the spring shifts the arms in the opposite direction and moves the valve to a position covering the passages 28 and 29. The movement of the first arm 38 is limited by the engagement of the stops 43 with the sleeve 22 and the movement of the second arm is limited by the engagement of the stops 56' with the valve stem 23. The operation is repeated continuously and the movement of the pistons drives the cleaner shaft 60 through the segmental gear 62, which meshes with the teeth in the connecting member 9. The cleaner element is thus oscillated over the surface of the windshield. The device may be placed in operation or cut off at any time by turning the valve stem 23 to open or close the valve 25.
- It is to be understood that the form of the invention herewith shown and described is to be taken as a preferred example of the same, and that various changes in the shape, size, and arrangement of parts may be resorted to without departing from the spirit of the invention or the scope of the subjoined claims.
- We claim:
1. A windshield cleaner comprising a cylinder having a relatively large opening, a closure plate adapted to be arranged over said opening, said closure plate being bored to provide an inlet passage adapted to be connected to a source of suction or pressure, and passages connected to the opposite ends of the cylinder, a manually controlled valve arranged in said inlet passage, the stem of said valve extending transversely of the cylinder, valve mechanism to connect either of said passages to said inlet passage, said valve mechanism including a pair of pivoted arms, and stops formed on said arms for engaging said valve stem to limit the movement of said arms.
  2. In a windshield cleaner, a cylinder provided with a relatively large opening intermediate its ends, the wall of the cylinder being extended to form flat faces, conduits extending from said opening to the opposite ends of the cylinder and arranged outwardly of said faces, the ends of said conduits being beveled, and a closure plate arranged over said opening, said closure plate being provided with passages alining with said conduits, and being further provided with beveled portions contacting with the beveled ends of said conduits.
  3. In a windshield cleaner, a casing, an actuating member arranged in said casing, and valve mechanism controlled by the movement of said actuating member to alternately connect said casing on opposite sides of said actuating member to a source of suction or pressure, said valve actuating mechanism comprising a pivotally mounted L-shaped arm, a valve carried by said arm, a second arm mounted on said pivot, said arms having limit parts extending adjacent each other, stop means common to both arms and related in a straddling manner to limit parts thereof, and a spring connected to the ends of the arms on opposite sides of the pivot, said second arm being operable by said actuating member.
  4. In a windshield cleaner, a casing, an actuating member arranged in said casing and valve mechanism controlled by the movement of said actuating member to alternately connect said casing on opposite sides of said actuating member to a source of suction or pressure, said valve actuating mechanism including an arm, a valve mounted on one end of said arm, a pivot pin received in said arm intermediate the ends of said arm, a second arm mounted on said pivot pin, said arm being provided with a cut-out portion, and a spring having its ends connected to said arms on opposite sides of said pivot pin, said cut out portion of said second arm receiving the body of said spring.
  5. In a windshield cleaner, a cylinder having a relatively large opening formed therein intermediate its ends, a closure plate normally closing said opening, said closure plate being provided with an extension disposed within said cylinder, said extension and said closure plate being provided with an opening transversely of said cylinder, a cleaner shaft arranged therein, a segmental gear arranged on the inner end of said shaft, a movable actuating member in said cylinder, connecting means between said movable actuating member and said valve mechanism, and a retaining member arranged on the outer end of said shaft to receive the cleaner element.

- ing member and said segmental gear, valve actuating mechanism arranged in said cylinder to alternately connect opposite ends of said cylinder to a source of suction or pressure, and a pivot pin mounted in said extension to support said valve actuating mechanism, said segmental gear being provided with an arcuate slot for the passage of said pivot pin.
10. 6. In a fluid pressure motor for windshield cleaners, a casing having an opening, a closure for the opening having a valve seat with passages opening therethrough from a source of suction and from the opposite ends of the casing, a piston operable in the casing, a valve cooperating with said seat for operatively applying fluid pressure to the piston, a valve carrier pivoted on said closure, a spring positioning member operable by said piston and swingingly mounted on the carrier pivot, a spring connecting said carrier and said positioning member and tensionably movable by the latter across the pivotal mounting thereof whereby said spring will act to swing said carrier and said positioning member in opposite directions, and a stop common to both the valve carrier and the positioning member for limiting the swinging movement of said carrier and said positioning member, said stop being arranged entirely to one side of the carrier pivot and said carrier and positioning member having portions extending to the specified side of said carrier pivot for cooperatively engaging the same.
35. 7. In a fluid pressure motor for windshield cleaners, a casing, a piston operable therein, automatic valve mechanism for operatively applying fluid pressure to the piston, said valve mechanism comprising a pivoted valve carrier, a pivoted spring positioning member, a spring connecting the carrier to said positioning member for being moved under tension by the latter to opposite sides of the pivot of said valve carrier, a stop, said positioning member and said carrier each having a pair of fingers straddling said stop for limiting their swinging movement, and means operable by the piston for alternately engaging the fingers of said positioning member.
50. 8. In a fluid pressure motor for windshield cleaners, a casing part having a valve seat and an overhanging support extending outwardly therebeyond, a valve, a valve carrier pivoted on the support and having a portion underlying the latter to carry the valve, a positioning member pivoted on the support and operable by a moving part of the motor, a spring connecting the carrier to the positioning member for movement under tension by the latter to opposite sides of the carrier pivot for effecting movement of the carrier, and stop means underlying the valve carrying portion of said carrier and engageable by the latter and also by said positioning member for limiting their swinging movement, said carrier and positioning member each having spaced limit fingers straddling said stop means for co-operating therewith in defining the extent of swinging movement of said carrier and said positioning member.
9. In a fluid pressure motor for windshield cleaners, a casing part having stop means extending therefrom, a valve, a valve moving member pivotally supported by said casing part and having limit portions straddling said stop means for defining the pivotal movement of said member, a second member pivotally supported by said casing part coaxially with said first member and having limit portions straddling said stop means for defining the pivotal movement of said second member, a spring connecting the two members and movable under tension by the second member to opposite sides of the pivot of the first member for effecting movement of the valve, said spring exerting opposing forces on said two members whereby normally they are urged in opposite directions and one limit portion of one member is engaging the opposite side of the stop means from that engaged by one of the limit portions of the other member, and means for operating said second member.
10. In a fluid pressure motor for windshield cleaners, a motor including a casing, a piston operable in the casing, a gear element fixed on said shaft and having an opening therein, said element being operatively connected and driven by the piston for operating the rock shaft, a pivot member secured to said casing and projecting freely through the opening of said element whereby the latter may oscillate uninterrupted by said pivot member, and automatic valve mechanism for operatively admitting fluid pressure to the motor, said valve mechanism including a lever pivoted on said pivot member, said gear element being guidingly interposed between said casing part and said valve mechanism lever, a second pivotally mounted lever, a spring connecting the two levers and movable under tension by one lever to opposite sides of the pivot member for effecting movement of the other lever, and a valve operable by the latter lever, said former lever being operable by and during movement of the piston.
115. In testimony whereof, we affix our signatures.

WILLIAM M. FOLBERTH.

CERTIFICATE OF CORRECTION.

Patent No. 1,665,204.

Granted April 10, 1928, to

FREDERICK G. FOLBERTH ET AL.

It is hereby certified that error appears in the printed specification of the above numbered patent requiring correction as follows: Page 3, line 97, claim 3, before the word "limit" insert the article "the"; page 4, line 25, claim 6, for the word "carried" read "carrier", and line 98, after the word "casing" insert the words and comma "a rock shaft journalled therein,"; and that the said Letters Patent should be read with these corrections therein that the same may conform to the record of the case in the Patent Office.

Signed and sealed this 15th day of May, A. D. 1928.

M. J. Moore,
Acting Commissioner of Patents.
